INVENTOR:
George F. Pawling
BY
William J. Faetham
ATTORNEY

UNITED STATES PATENT OFFICE.

GEORGE F. PAWLING, OF PHILADELPHIA, PENNSYLVANIA.

FURRING CONSTRUCTION.

Application filed September 6, 1924. Serial No. 736,245.

This invention, generally stated, relates to building construction, especially concrete structures, and has more particular relation to ceiling construction.

As at present practiced, it is the accepted custom, in the construction of a ceiling of concrete, to wire metal lath to the furring prior to the application of the concrete. This not only consumes much valuable time, 5 is more or less expensive, and requires the services of a skilled workman, but, from an engineering view-point is not especially desirable.

The leading object of the present invention is to overcome the above disadvantageous features and provide an efficient, practical and inexpensive system of metal lath attachment to sectional furring and one in which unskilled workmen may readily and 10 expeditiously apply metal lath to ceiling supporting furring. A further object resides in the provision of a novel form of furring for effecting the results sought by said leading object. Other and further objects not 15 at this time appearing will be described hereinafter.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view, principally in section illustrating a ceiling structure embodying the invention.

Fig. 2, is a fragmentary view in section of certain of the parts shown in Fig. 1, and

Fig. 3, is a view in plan of certain of the parts shown in Fig. 1.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the practice of the invention I make use of a novel and specially designed fur-

ring. This furring comprises a plurality of sections of channel-steel the ends of which may be and as shown are shaped for interlocking relation and the faces of which have struck out therefrom metal-lath supporting 60 tongues, said ends and tongues being provided at the time of making the furring. The furring sections form a continuous member for the whole length of the ceiling. The numeral 1 designates the supporting 65 structure which may be any of the conventional types although I prefer to employ bar-joist. To these bar-joists I wire the furring 2. One end of each section of furring, which is of U-shaped cross-section, is 70 shaped to provide a penetrating portion 3 and the opposite end is provided with a receiving portion 4. These portions are formed at the time of making the furring by squeezing the ends to desired configuration. The side walls of these portions 3 and 4 are laterally apertured at 5 so that when the ends of the sections of furring are 75 cooperatively fitted together with the apertures 5 in register, cotter pins 6, or the like 80 may be employed to interlock the sections with respect to one another. The wires for securing the furring to place are designated 7. The under face of each section of furring has stamped therefrom a plurality of spaced 85 tongues each bent downwardly at 9 and extended in a horizontal manner at 10 to provide a series of metal-lath supports. The metal-lath 11 I prefer to employ is of the type termed permanent steel forms and is 90 provided with a plurality of loops 12. By causing each separate furring section to engage with these loops prior to positioning said metal lath with respect to said joists an 95 expeditious, simple and effective attachment may be secured by unskilled workmen which is an important item in this class of work under discussion. Concrete 13 is then applied as usual.

It will now be apparent that I have devised a novel and useful construction which embodies the features of advantage enumerated as desirable in the statement of the invention and the above description and while I have in the present instance shown and 100 described the preferred embodiment thereof which has been found in practice to give satisfactory and reliable results, it is to be understood that the same is susceptible of modification in various particulars without 105 110

departing from the spirit or scope of the invention or sacrificing any of its advantages.

What I claim is:

- 5 1. In a ceiling construction of the character stated, a supporting structure, furring having adjacent ends fitted together and suspended from said supporting structure, the furring consisting of a plurality of sections to form a continuous member for the whole length of the ceiling, said furring being provided with metal-lath supporting clips, and metal lath arranged beneath said furring and engaged by said clips.
- 10 2. In a ceiling construction of the character stated, a supporting structure, furring having adjacent ends fitted together and suspended from said supporting structure, the furring consisting of a plurality of sections to form a continuous member for the whole length of the ceiling, said furring being provided with metal-lath supporting clips, pins passing laterally through said furring ends, and metal-lath arranged beneath said furring and engaged by said clips.
- 15 3. In a ceiling construction of the character stated, a supporting structure, furring of U-shaped cross-section suspended from

said supporting structure, the furring consisting of a plurality of sections to form a continuous member for the whole length of the ceiling, the furring bottom having struck out therefrom metal-lath supporting clips and the adjacent ends of said furring being fitted one within the other, pins extended laterally through said fitted ends and metal-lath arranged beneath the furring and supported by said clips.

4. Furring comprised of substantially U-shaped sections arranged end to end throughout the whole length of a ceiling and comprised of channel-steel the adjacent ends of which sections are shaped to cooperatively nest one within the other by contracting the end of one section and bending the end of a companion section to fit within said contracted end and which nested sections are apertured for pin reception, the bottoms of said sections having struck out therefrom metal lath engaging clips, and cotter pins engaging said apertured parts and extended laterally through each of said adjacent sections for interlocking of said nested parts.

In testimony whereof, I have hereunto signed my name.

GEO. F. PAWLING.
